UNITED STATES PATENT OFFICE

THOMAS W. STONE, OF FORT WAYNE, INDIANA, ASSIGNOR TO WESTERN GAS CONSTRUCTION COMPANY, OF FORT WAYNE, INDIANA, A CORPORATION OF INDIANA

CHARGING-DOOR CONSTRUCTION

Application filed March 17, 1922. Serial No. 544,597.

This invention relates to a charging door construction that is of especial utility in conjunction with gas generators, such as the generators of water gas sets; the invention has for objects to provide a construction by which the charging door may be securely clamped in position to close the charging hole of the apparatus to which the door is applied, the door being clamped over the charging hole in such manner as to prevent the door from moving out of its closed position and to prevent leakages from the generator past the door.

In addition to the general objects recited above, the invention has for further objects such other improvements and advantages in construction and operation as are found to obtain in the structures and devices herein-after described or claimed.

In the accompanying drawings forming a part of this specification and showing, for purposes of exemplification, a preferred form and manner in which the invention may be embodied and practiced, but without limiting the claimed invention to such illustrative instance or instances—

Figure 1 is a plan view of a door construction embodying features of the invention;

Fig. 2 is a vertical sectional elevation of the construction illustrated in Fig. 1;

Fig. 3 is a horizontal section taken in a plane indicated by the line 3—3 of Fig. 2; and

Fig. 4 is a detailed vertical section taken in the plane indicated by the line 4—4 of Fig. 1.

The same characters of reference designate the same parts in each of the several views of the drawings.

In the illustrated embodiment of the invention, the improved door construction is applied to the charging hole of a gas generator, this being an especially useful application of the invention. For convenience, the present description will be confined to this use of the invention. Features of the improved door construction are, however, capable of other valuable applications, consequently, the invention is not confined in its scope to the specific use and specific embodiment herein described as an illustrative example.

Referring to the drawings, and more particularly to Fig. 2, there is shown at 11 a

charging chute ordinarily located at the top of a gas generator, the chute 11 projecting through the charging hole of the generator and being provided at its upper end with an outwardly extending horizontal flange 12 which rests upon and is supported by lugs 13 which project inwardly from the inwardly-extending flanged member 14 mounted on the frame 15, the latter being mounted upon the top of the generator and surrounding the charging hole. The top 16 of the aforesaid flange 14 affords a seat for the charging door when the latter is in closed position. Positioned at diametrically opposite points on the door frame 15 and conveniently formed integral with the upper casting thereof are abutments 17. Each such abutment 17 is provided with a horizontally extending pocket 18 open at one end, as shown at 19, and with an overhanging top 20 which forms the top 70 of the pocket 18.

The main body of the charging door is preferably constituted of the usual convex plate 21 provided with a depending flange 22 adapted to rest on the seat 16 when the door is closed. For moving the door 21 into and out of its closed position on the seat 16, there is provided a crossbar 23 mounted at its opposite ends on truck wheels 24 which run on tracks 25, mounted above the generator for permitting the door 21 to be rolled into and out of position for closing the charging hole of the generator. At its opposite ends the crossbar 23 is provided with depending and inwardly bent arms 26 which enter the pockets 18 of the abutments 17 when the door 21 is in position for closing the charging hole.

The door 21 is suspended from the center of the crossbar 23 by a T-screw 27 the threaded portion of which passes through a threaded socket 28 which extends through the crossbar 23. At its lower end the T-screw 27 is provided with a head 29 located within a socket 30 in the center of the top of the door 21. The top of the socket 30 is closed by a cover plate 31 having a bore for the reception of reduced portion 32 of the T-screw above the head 29, but extending over the head to prevent movement of the head out of the socket in the upward or lowering move-

ments of the T-screw to lift or to lower the door 21.

With the above described construction, the door 21 is moved into position for closing the charging hole by moving the crossbar or carriage 23 along the tracks 25 until the inwardly-bent arms 26 enter the pockets 18 of the abutments on the opposite sides of the door frame. The door is then lowered into the closing position by screwing down the T-screw 27. As the T-screw is tightened, the carriage 23 is lifted off the tracks 25 and the arms 26 engage the tops 20 of the pockets 18, whereby the carriage is rigidly clamped to the door frame and the door is rigidly clamped over the charging hole from the thus rigidly clamped carriage. The door may be readily removed from the charging hole by loosening up the T-screw so as to permit the carriage to fall back onto the tracks 25 and then, by further movement of the T-screw, the door may be lifted from the charging hole. The carriage supporting the elevated door may then be moved clear of the charging hole.

In order to protect the door 21 from the heat of the generator, the door is provided with a false bottom or protecting plate 33 removably secured to the door in a peculiarly efficient manner. The protecting plate 33 may be provided with cross ribs 34 for strength. Around its periphery the protecting plate is provided with a series of notches 35. These notches when positioned in registry with a companion series of lugs 36 inwardly-projecting from the surrounding flange 22 of the door 21, permit the plate 33 to be inserted into the concave face beneath the door and then to be turned so that the notches do not register with the lugs and the latter support the plate underneath the door. The plate provides an air or gas space between it and the main body of the door and thus serves to protect the door from the high temperatures of the generator.

Means are provided for locking the plate 33 in the position in which it is supported by the lugs 36, the locking means acting to prevent the plate from turning accidentally to bring the notches 35 into registry with the lugs 36, so that the plate is prevented from falling out of its position underneath the door. Between two of the notches 35 of the protecting plate there is provided an additional smaller notch 37 hereinafter called the "locking notch". One of the supporting lugs 36 is provided with a locking lug 38 which registers with and enters the notch 37 when the notches 35 are out of registry with the lugs 36. By reason of the engagement of the lug 38 with the notch 37, the plate is prevented from turning in both directions and is thus securely held in position underneath the door. In applying the plate, the notches 35 are placed in registry with the

lugs 36, the plate is moved into the door space so that the lugs 36 are positioned beneath the notches, and the plate is then turned so that the locking lug 38 enters the locking notch 37.

The invention as hereinabove set forth is embodied in a particular form of construction, but may be variously embodied within the scope of the claims hereinafter made.

I claim:

1. Means for closing the openings of heated chambers, comprising: spaced rails, abutments arranged alongside said rails, a door frame between said abutments, a crossbar having wheels thereon that run on said rails, said crossbar having extensions beyond said wheels to form lugs that engage said abutments, said crossbar having a screw thereon, a cover on the lower end of said screw, whereby when the extended lugs of the crossbar are in position with said abutments, and the screw is tightened up, the extension lugs engage the abutments, the wheels are lifted slightly off the track as the cover clamps down on the main frame of the heated chamber and as the screw is reversed in opening the door, the lugs on the crossbar loosen in the abutments, the wheels settle down on the rails, the cover is raised until its weight, suspended from the crossbar, is carried by the wheels on the rails.

2. In a charging door construction for furnaces the combination of rails at each side of the charging hole, a wheeled cross bar supported on said rails and adapted to be positioned over said charging hole, a door for the charging hole carried centrally by said crossbar, and means for clamping said door over said charging hole by movement of the door away from said cross bar and by movement of said wheeled cross bar away from the rails and charging hole.

3. In a charging door construction for furnaces the combination of supports at each side of the charging hole, a cross bar movable on said supports from a position over the charging hole to a position away from the same, a door for the charging hole carried by said cross bar, fixed abutments at each side of the charging hole, arms on said cross bar adapted to interlock under said abutments when said hole is closed, and means for moving the door and cross bar away from each other to press said arms upward against said abutments and to press the door into tight closing position.

4. In a charging door construction for furnaces the combination of supports at each side of the charging hole, a cross bar movable on said supports from a position over the charging hole to a position away from the same, a door for the charging hole carried by said cross bar, fixed abutments at each side of the charging hole, arms on said cross bar adapted to interlock under said abutments

when said hole is closed, and rotary means for moving the door and cross bar away from each other to press said arms upward against said abutments and to press the door into tight closing position.

5. In a charging door construction for gas generators the combination of supports at each side of the charging hole, a cross bar movable on said supports from a position over the charging hole to a position away from the same, a door for the charging hole carried by said cross bar, fixed abutments at each side of the charging hole, arms on said cross bar adapted to interlock under said abutments when said hole is closed, and a screw for moving the door and cross bar away from each other to press said arms upward against said abutments and to press the door into tight closing position.

10 6. In combination with a furnace having a charging hole, a pair of abutments located adjacent to said charging hole, a door supporting member adapted to be moved into position over and supported on each side of said charging hole, a door supported by said member for closing the charging hole, and means for lowering the door into closing position, said door lowering means being further operable to elevate said door supporting member 15 to clamp the same against said abutments and to clamp said door against said charging hole.

20 7. A closure member for heated chambers comprising, in combination: a door frame having fixed clamping abutments at each side thereof, a door carrying member movable relative to said abutments and having parts adapted to engage said abutments, a door carried by and depending from said door carrying member, means connecting said door to said door carrying member, said means being operable to lower said door on its frame and upon further operation thereof said means raising said carrying member until said parts thereon engage said abutments to 25 thereby clamp said door to its frame, said means being operable thereafter to release the carrying member from said clamping engagement and also to raise said door from its frame.

30 8. A closure for heated chambers comprising in combination: a door frame having fixed clamping abutments at each side thereof, a door carrying member movable relative to said abutments and having parts adapted to engage said abutments, said carrying member having wheels thereon and tracks supporting said wheels whereby said door carrying member is positioned over and removed from said door frame by a lateral movement relative to said door frame, a door carried by and depending from said door carrying member, means connecting said door to said door carrying member, said means being operable to lower said door on its frame and upon further 35 operation thereof to raise said carrying mem-

ber to engage said parts thereon with said abutments to thereby clamp said door to its frame, said means being operable thereafter to release the carrying member from said clamping engagement and also to raise said door from its frame.

70 In testimony whereof I have hereunto set my hand.

THOMAS W. STONE.
